UNITED STATES PATENT OFFICE.

WLADYSLAW LYJAK, OF BRADDOCK, PENNSYLVANIA.

NECKTIE STRETCHER.

Application filed January 27, 1927. Serial No. 163,923.

My invention relates to improvements in necktie stretchers, and more particularly to that class of necktie or cravat stretchers designed to be inserted into the tie for the purpose of exerting a stretching action on the tie to remove wrinkles, etc., caused by use of the necktie, or to maintain the tie in its original form.

The prime object of the present invention 10 is to provide a necktie stretcher of the character stated which is of simple and inexpensive construction, and one that may be readily and advantageously employed in connection with neckties varying in size.

15 In the accompanying drawings, which illustrate applications of my invention:

Fig. 1 is an elevational view of a necktie, showing the stretcher embodying my invention applied thereto;

20 Fig. 2, an elevational view of a necktie stretcher constructed in accordance with my invention;

Fig. 3, a similar view, showing a modified form;

25 Fig. 4, a detail elevational view of a wedging means;

Fig. 5, a view similar to Fig. 4, showing a modified form of wedging means; and

30 Fig. 6, a sectional view taken on line VI—VI of Fig. 2.

Referring to the drawing, and first to the form of Fig. 2, 5—5 designates a pair of members, each formed with a bent-over portion *a* and a portion *b*. These members are 35 preferably made from some suitable metal, as aluminum, and constitute the body of the stretcher. As illustrated, members 5 are pivotally or hingedly connected at one end of the body by an eyelet or rivet 6, whereby they may be moved relatively to each other as desired, to accommodate the stretcher to different widths of ties to which it may be applied.

It will be noted that the bent-over portions 45 *a* will, in connection with portions *b*, form channelled portions on opposite sides of the body, and that the bent-over portions *a* are of gradually decreasing width as they approach the pivot or hinge connection joining the two members together. By decreasing the width of the bent-over portions *a*, as described, the members may be conveniently joined together at one end of the structure without cutting away parts and without

forming an undesirable thickened portion 55 at the point of connection. The upper end portions of the members 5 are preferably rounded, as shown at 7, to eliminate sharp corners or edges that might catch into the material of the tie and tear the material 60 when the device is being inserted into the necktie.

Located within the body and designed to have a sliding movement therein, is a removable wedging member 8. Member 8, as shown, is formed with two enlarged curved end portions 9 and 10. The portion 9 is of greater diameter than the portion 10; both portions however, have curved edge portions 65 adapted to be entered in and slide within the channel portions of the respective members 5. It will be understood that a movement of the member 8 within the stretcher towards the connecting means 6 will spread the members 5 apart, so that the stretcher will be expanded to properly stretch and shape the necktie.

If the device is to be employed for stretching neckties of large width, the larger end portion 9 is disposed nearest the pivot point. 80 In other words, the position of the end portions 9 and 10 is reversed from the position shown by Fig. 1. While the body or the main portion of the member may be varied, it is 85 essential that the curved engaging portions of the wedging member be retained.

In Fig. 5 of the drawings, I have shown a modified form of wedge member. In this latter form, I employ a strip member 8^a to which circular enlarged end members 9^a 90 and 10^a are respectively secured to the ends thereof by pins or eyelets 11.

In the form of Fig. 3, the members 5^b—5^b are connected by a transverse member 12, to which the said members are connected by 95 eyelets 13.

The members 5, as well as the wedging means, are made of relatively thin, somewhat flexible material. The device as a whole, however, is sufficiently rigid to produce the 100 desired stretching, and may be readily inserted within the large end of the tie, as shown by Fig. 1, and the wedging means moved on the body of the stretcher until the tie is properly stretched. As an aid in guiding the wedging means, the wedge member may be first placed in the position shown by the dotted lines of Fig. 3, and then slid into 105

the desired position, but it is not necessary that the wedge be thus positioned before being moved relatively to the body.

What I claim is:

1. In a necktie stretcher, a pair of relatively movable connected channel-like members, and a removable wedging member positioned within the stretcher body, said wedging member having a curved contacting channel en-
10 gaging portion.

2. In a necktie stretcher, a pair of rela-

tively movable members each having a bent-over portion to provide a channel-like portion thereon, a hinge connection for movably connecting the members, and a removable wedge positioned within the stretcher and having a curved contact channel engaging portion, said bent-over portions of the said members decreasing in width as they approach the hinge connection.

In testimony whereof I affix my signature.

WLADYSLAW LYJAK.
